IMPROVEMENT IN BLOWHEAD

Earl L. Lowe, Winchester, Ind.

Application March 25, 1950, Serial No. 151,899

5 Claims. (Cl. 49—18)

1

The present invention relates to improvements in nozzle structures particularly useful and adapted for blowing and internally cooling articles of glassware in the blowheads in which glassware is adapted to be given its final shape.

My invention reduces strain and check marks in the bottle finish by causing air to swirl and move around bottle finishes in such a manner as to distribute air circulation in a more even manner than now accomplished by nozzles of other blowheads.

This object is accomplished, as hereinafter described and shown, by a simply constructed nozzle easily manufactured and operated, and having air ports constructed on an angle to the periphery of the nozzle.

Referring to the drawings attached hereto for the purpose of disclosing certain embodiments illustrative of my invention, in which

Figure 1 is a longitudinal sectional view of a blowhead embodying features of my invention.

Figure 2 is a plan view of the nozzle showing the lateral angular displacement of air ports within for airstream flow.

Figure 3 shows my invention in side elevation view.

Figure 4 is a bottom view of my invention showing air ports on periphery and center opening.

In the embodiment of my invention as illustrated, the nozzle 10 as shown in Figure 1 is adapted to be utilized in a blowhead 9 or the like and mold 13 of conventional design for holding a glass bottle after initial forming.

My nozzle 10 is made of suitable metal and is in the form of a single major element which in Figure 1 and Figure 3 has the appearance of a large bolt with head portion 15, bevel portion 23, concave portion 26, threaded shank portion 16. Associated with said nozzle 10 is a lock washer 14, and lock nut 15' to secure my invention within a collar 12 and lock ring 12' of the blowhead 9 which is not of my invention but of a conventional type.

It is believed that other means to hold the said invention within the collar such as a through pin or the like, could be used and is contemplated without departing from the scope of my invention.

Nozzle 10 has a center passage 17 bored of a relatively larger diameter than passage 18 which continues through nozzle 10 to the outer end of head portion 15 as indicated in Figure 1. The central passage 17 includes an underbored portion within head 15 forming a connecting well

17' or undercut portion, for passages 17, 18 and radiating exit passages 19. A plurality of passages 19 are bored to extend from well 17' or undercut portion to the periphery of bevel 23, 5 near the edge of concave top 18'. Passages 19 are adapted to direct a portion of cooling airstream 21 from within nozzle 10 to the exterior of the same near the bottle finish area 22 as designated in Figure 1. By reason of the angular 10 position of passages 19 that portion of airstream 21 emerging from said passages adopt a swirling circuitous path around finish 24 in area 22, as indicated in Figure 2, at the same time another portion 20 of cooling airstream 21 is directed 15 vertically into the interior of bottle finish 24 thus achieving a substantially even distribution of airstream 21 on both sides of finish 24 simultaneously. Airstream 20 directed vertically into bottle 25 bouncing upwards is reflected back by a 20 concave lower face portion 26 of the nozzle 10 thus assisting in the complete distribution of air around finish 24.

In order to reduce budging, strain marks and 25 check marks in a bottle finish 24 it is essential that cooling air 21 be substantially evenly distributed in adequate quantity on both sides of finish 24 as described herein.

Having shown and described my invention, I claim

1. A nozzle comprising an element substantially bolt shaped in appearance having a head portion and a threaded shank portion, said element being centrally bored with connecting passages of different diameters, said passages joined within said head portion at an undercut portion, a plurality of passages of smaller diameter than said bore starting from said undercut portion at an angle thereto and extending to the outer side of said head portion, said head portion formed with a concave lower face portion, said nozzle being a portion of a blowhead adapted to contain a bottle finish therein and means adapted to secure said element to other elements of the blowhead.

2. In a bottle finish blowhead having a bottle finish receiving recess, a nozzle for distributing cooling air, said nozzle being positioned within said recess and including a shank portion connected to said blowhead, a central bore through said shank portion communicating with an air supply passage of said blowhead, an enlarged head integral with said shank portion and having a reduced continuation of said central bore therethrough, an undercut portion formed at the junction of said central bore and its reduced continu-

ation, angularly disposed passages extending downwardly through said head portion from said undercut portion, said passages being disposed at angles to planes passed through their upper centers and the axis of said central bore, said reduced continuation of said central bore being adapted to supply air to an interior of a bottle finish simultaneous with swirling movement of air from said passages about the exterior of said bottle finish.

3. In a bottle finish blowhead having a bottle finish receiving recess, a nozzle for distributing cooling air, said nozzle being positioned within said recess and including a shank portion connected to said blowhead, a central bore through said shank portion communicating with an air supply passage of said blowhead, an enlarged head integral with said shank portion and having a reduced continuation of said central bore therethrough, an undercut portion formed at the juncture of said central bore and its reduced continuation, angularly disposed passages extending downwardly through said head portion from said undercut portion, said passages being disposed at angles to planes passed through their upper centers and the axis of said central bore, said reduced continuation of said central bore being adapted to supply air to an interior of a bottle finish simultaneous with swirling movement of air from said passages about the exterior of said bottle finish, said nozzle having a concave lower face portion for reflecting air down into said bottle finish.

4. In a bottle finish blowhead having a bottle finish receiving recess, a nozzle for distributing cooling air, said nozzle being positioned within said recess and including a shank portion connected to said blowhead, a central bore through said shank portion communicating with an air supply passage of said blowhead, an enlarged head integral with said shank portion and having a reduced continuation of said central bore therethrough, an undercut portion formed at the juncture of said central bore and its reduced

continuation, angularly disposed passages extending downwardly through said head portion from said undercut portion, said passages being disposed at angles to planes passed through their upper centers and the axis of said central bore, said reduced continuation of said central bore being adapted to supply air to an interior of a bottle finish simultaneous with swirling movement of air from said passages about the exterior of said bottle finish, said head portion having a beveled lower peripheral edge, said beveled edge being in spaced parallel relation to said undercut portion.

5. A blowhead comprising a collar having a central bottle finish recess therein, a nozzle carried by said collar, said nozzle having a shank portion connected to said collar and a head portion disposed in said recess, said shank portion having a central bore therethrough adapted to be communicated with a cooling air source, a central passage through said head portion, downwardly and outwardly directed passages opening through outer portions of said head portion, each of said downwardly and outwardly directed passages being at an angle to both the vertical axis of the nozzle and a plane passed through said vertical axis, said passages being adapted to simultaneously direct cooling air into the interior of and in a swirling movement about the 10 exterior of a bottle finish.
